UNITED STATES PATENT OFFICE.

GEORGE W. LAMPMAN, OF SWANTON, VERMONT.

DESIGN FOR A PLAYING-CARD.

SPECIFICATION forming part of Design No. 22,640, dated July 18, 1893.

Application filed March 2, 1893. Serial No. 464,455. Term of patent 14 years.

To all whom it may concern:

Be it known that I, GEORGE W. LAMPMAN, a citizen of the United States, residing at Swanton, in the county of Franklin and State of Vermont, have invented and produced a new and original Design for Playing-Cards, of which the following is a specification.

In the annexed drawing I have shown a face view of a card with my design.

The leading feature of my design consists of the bust figure of Christopher Columbus accompanied by representations of a cross and of the earth. As illustrated in the drawing, the bust is draped in the costume of the fif-

teenth century, and a cross, B, rises from the left shoulder. At the base of the bust is a representation of the earth, C, resting on a scroll or chart, D. The bust figure is duplicated, as shown, the duplicate figures having a common base.

Having thus described my design, what I claim is—

The design for playing cards herein described and shown.

GEORGE W. LAMPMAN.
